UNITED STATES PATENT OFFICE.

LEO P. VANCE, OF ROCK ISLAND, ILLINOIS.

GASOLENE-ENGINE.

1,090,177.

Specification of Letters Patent. Patented Mar. 17, 1914.

Application filed September 21, 1912. Serial No. 721,596.

To all whom it may concern:

Be it known that I, LEO P. VANCE, a citizen of the United States, residing at Rock Island, in the county of Rock Island and State of Illinois, have invented certain new and useful Improvements in Gasolene-Engines, of which the following is a specification, reference being had therein to the accompanying drawing.

10 This invention relates to internal combustion motors, and has special reference to a two cycle internal combustion motor arranged to operate in connection with an automatic fuel pump.

15 The principal object of the invention is to improve the efficiency and economy of the internal combustion motor.

The second object of the invention is to provide means for injecting fuel into the cylinder at the moment ignition takes place for the purpose of doing away with the trouble of premature ignition.

20 The third object of this invention is to dispense with timing gears and exhaust valves.

25 With the above and other objects in view this invention consists in general of certain novel constructions, combinations and arrangement of parts as will be hereinafter 30 fully described, illustrated in the accompanying drawings, and specifically claimed.

In the accompanying drawings, like characters of reference indicate like parts in the several views, and:—Figure 1 is a vertical section taken through the engine constructed in accordance with this invention, certain of the parts being shown in elevation. Fig. 2 is a horizontal section through the upper part of the engine. Fig. 3 is an enlarged detail view of the compression piston and its parts. Fig. 4 is a detail horizontal section partly broken away through the compression piston.

35 In carrying out the objects of this invention, there is provided a crank casing 10 of the closed type, and in this crank casing is journaled a crank shaft 11 having the usual crank 12 which is connected by means of a piston rod 13 with the pin 14 of a piston 15. 40 This piston is of the usual hollow type and works in a cylinder 16 surrounded by a water jacket 17. On the top of the cylinder 16

is positioned an auxiliary cylinder 18 having the usual water jacket 19, and the bottom of this cylinder 18 is provided with an inwardly extending flange 20. The cylinder 18 carries the head 21 wherein is a stuffing box 22 provided with a packing 23. This stuffing box 22 is closed in by a cap 24 secured to the cylinder head by suitable bolts 25. 55 The head 21 is provided with a downwardly extending flange 26 having an interior diameter equal to the interior diameter of the head and stuffing box, and slidably mounted in the head of the stuffing box and the flange 60 is a piston 27 which is formed integrally with a piston 28 by preference, the latter working in the cylinder 18. Both the piston 28 and the piston 27 are hollow as shown clearly in Fig. 3, and through the walls of 65 the piston 27 extend openings 29 which communicate with the chamber 30 formed in the hollow piston 27 and with a chamber 31 surrounding said hollow piston.

The lower end of the piston 28 is provided 70 with an opening forming a barrel seat 32 wherein is seated a valve 33 provided with a stem 34 which extends upward in the upper end of the piston 27 passing through a septum 35. The upper end of this valve stem 80 34 is surrounded by a coil spring 36, and above the spring is provided a collar 37 secured by a cotter pin 38. The spring 36 bears at one end against the septum 35 and at the other end against the collar 37 so that 85 the valve 33 is normally held closed. Access is had to the collar and spring by means of a plug 39 fitting in the threaded opening of the upper end of the piston 27.

The crank casing is provided with a port 90 40 from which leads a passage 41 which has its upper end connected to a port 42 giving access to the chamber 31. A check valve 41 is provided so that air may be drawn into the crank casing. This check valve is of the 95 usual type and comprises a perforated casting forming a rest for one end of the spring yieldably holding the inwardly opening valve stem in a closed position.

On top of the cap 24 is a valve casing 43 100 which opens into the cap, a seat 44 being formed at the lower end of said opening. A valve 45 is arranged to rest on this seat when the valve is closed, and is provided with a

2
stem 46 extending upward through the valve casing and having on its upper end a collar 47 between which and the casing is a spring 48 so that the valve is normally closed. An air intake opening 49 is made in the valve casing to admit air thereto, and the cap 24 is provided with a port 50 which is connected by a pipe 51 with a port 52 formed on the casing 53 of the mixing valve, the latter being provided with the usual needle valve 54 operated by means of the bell crank lever arrangement 55 which is connected by a reach rod 56 to the valve cam-shaft. The mixing valve casing is likewise provided with a port 57 to which is connected the pipe 58 leading from the supply of gas or the like. The pipe 58 is provided with a suitable check valve to prevent back flow of gas from the valve casing to the gas supply. The cylinder 16 is provided intermediate its ends with the exhaust ports 59, and these ports may or may not be connected to suitable exhaust pipes, as preferred.

In the operation of this device the first instroke draws into the crank-case air only through the check valve (not given on drawing) and compresses air in the cylinder 16 and below pistons 28 and 27 forcing them up, compressing air above piston 27. It is to be noted since the area of piston 28 is greater than that of piston 27, the pressure above piston 27 is greater than the compression or explosive pressure in cylinder 16 and below piston 28. Now as piston 15 reaches a point just before dead center fuel admission valve 54 opens and sprays air mixed with the fuel in mixing valve casing 53. Now as no great amount of fuel is in the cylinder 16 at one time, the burning of the fuel will not be in the nature of an explosion; but will last as long as there is fuel in mixing valve casing 53; and valve 54 is open, about one tenth of the forward stroke. The method of burning is similar to a gas burner, the supply and amount of fuel entering the mixing valve casing 53 may be regulated by choking air intake 49. As piston 15 reaches the position shown in Fig. 1 the explosion takes place then piston 15 will descend on the out stroke and compress the air that is in the crank-casing 10, passage 41, 42 and in chamber 31. When piston 15 reaches a point about 10° before it reaches dead center the exhaust 59 starts to open. Now as the pressure in cylinder 16 falls below the pressure in crank-casing 10, air passage 41 and chamber 31 and above piston 28 it will force piston 28 down till ports 29 in piston 27 fall below flange 26, it will then enter ports 29 and chamber 30. Now at this time the valve 33 opens and this air flows inward assisting in the scavenging of cylinder 16; as pistons 27 and 28 descend it forms a vacuum above piston 27 and in air pipe 51 and in mixing valve-casing 53

drawing in fresh air through valve 45 and a small quantity of fuel into mixing valve casing 53 ready for the next cycle.

Having thus described the invention, what is claimed as new, is:

1. An engine comprising a casing, a lower cylinder above said casing, an upper cylinder above said lower cylinder, the partition between said cylinders being perforated to permit communication between said cylinders, a hollow cap for said upper cylinder, a piston head slidably mounted in said lower cylinder, a crank shaft passing through said casing, a link connecting said crank shaft with said piston head, a piston head slidably mounted in said upper cylinder and provided with a hollow core extending into said hollow cap, a valve in said core for normally closing an opening in the bottom thereof, the upper portion of said core being provided with perforations for permitting access to the interior thereof, means for permitting communication between said casing and said upper cylinder, and means for introducing fuel into the upper portion of said lower cylinder.

2. An engine comprising a casing, a lower cylinder positioned above said casing and communicating therewith, an upper cylinder positioned above said lower cylinder and communicating therewith, a collar extending inwardly from the upper wall of said upper cylinder and closing an opening formed therein, a hollow cap closing an opening formed in the wall of said upper cylinder, a piston head slidably mounted in said upper cylinder and provided with an extension adapted to close the opening permitting communication between said upper and lower cylinders when said upper piston is in a lowered position, a hollow core in said upper cylinder extending through said collar into said hollow cap, a valve controlling an opening formed in the bottom of said piston, the walls of said core being provided with inlet openings, a pipe permitting communication between said casing and the upper portion of said upper cylinder, a crank shaft passing through said casing, a piston in said lower cylinder, a piston rod connecting said crank shaft with said last mentioned piston, and means for introducing fuel into said lower cylinder above said last mentioned piston.

3. An engine comprising a casing, a lower cylinder above said casing, an upper cylinder above said lower cylinder, a cover plate for said upper cylinder provided with a central opening, an inwardly extending collar closing said opening, a hollow cap covering said opening, a hollow piston in said upper cylinder, a core in said piston extending through said collar into said hollow cap, a partition in said core, the lower portion of said core being provided with a plurality of

openings adjacent said partition and with an opening in its end, a valve for closing the opening in the end of said core, a stem extending from said valve through said partition, a spring surrounding said stem above said partition and engaging the same for normally holding said valve in a closed position, a piston in said lower cylinder, operating means for said lower piston, and means

for permitting communication between said 11 casing and said upper cylinder.

In testimony whereof I hereunto affix my signature in presence of two witnesses.

LEO P. VANCE.
